UNITED STATES PATENT OFFICE

AIMO JOHANNES LAHTI, OF JYVASKYLA, FINLAND

CARTRIDGE CASE

Application filed December 26, 1930, Serial No. 504,925, and in Finland July 5, 1930.

The present invention relates to such a cartridge case for fire-arms, which inserted in the feeding aperture of the fire-arm automatically feeds the cartridges into the weapon. The cartridge case according to the invention is preferably made in the shape of a cylindrical container, inside of which the cartridges are arranged either in a cylindrical or a spiral guiding channel side by side and parallel to the axis of the container. A spring acted feeding drum, fitted in the guiding channel, feeds the cartridges into the feeding chamber at the periphery of the case. The invention comprehends also an indicator, which indicates the number of cartridges in the case and is depending on the motion of the case.

The accompanying drawings illustrate schematically some ways of carrying out the invention in practice, and in it:

Fig. 1 shows the end view of a so called single row cartridge case according to the invention, the cover of the case being removed.

Fig. 2 shows in side elevation a section on center line of the above case. The key of the case is shown inserted in place.

Fig. 3 shows the key of the case as seen from below.

Fig. 4 is an end view section of a so called double row case.

Fig. 5 shows the double row case in side elevation.

Fig. 6 shows the cartridge number indicator fitted into a cartridge case according to the invention.

The single row case according to Fig. 1 is made up of a round case 1, to the axis of which is fixed at its flange 2 and by means of screws or rivets 3 the case shaft 4 extending throughout the length of the case. Inside of the case 1 rolls on said shaft 4 the feeding drum 5 on the periphery 7 of which there is a flange 6. The guide channel 8 for the cartridges is built up of the case 1, the periphery 7 and flange 6 of the feeding drum 5, and the detachable cover 9 of the case 1. On the inside of the drum periphery 7 there is a spiral spring 10, wound around the drum shaft 4, the inner end of said spring 10 being

fixed to the shaft 4 and the outer end to the periphery 7 of the drum 5. The feeding spring 10 tends to turn the feeding drum 5 in Fig. 1 counter-clockwise. To the periphery 7 of the feeding drum 5 is attached a feeding shoulder 11 extending in the guiding channel 8. Said shoulder 11 pushes the cartridges, side by side into the channel 8, ahead along the guiding channel 8. To the inside of the peripherical mantle of the case 1 there is furthermore fixed a guiding shoulder 13, which guides the cartridges 12 out from the channel 8 and into the feeding chamber 14. The feeding chamber 14 has an aperture 15, through which the loading mechanism of the fire-arm (not shown in the drawings) operates on the cartridge pushing it axially into the cartridge chamber.

The operation proper of the cartridge case should be clear from the above. By action of the feeding spring 10 the feeding drum 5 rotates counter-clockwise; the feeding shoulder 11 pushes the cartridges 12 into the feeding chamber 14 from where these are fed further into the cartridge chamber.

The filling of the cartridge case is carried out as follows: When the case cover 9 is removed the guiding groove 8 is freely accessible. The case key 16, shown in Figs. 2 and 3, which is furnished with a joint handle 17 as per drawings, or of some other suitable construction, is pushed into the case in such a way that the case shaft 4 sticks into a centric bore 18 of the key 16. The pins 19 in the key 16 engage corresponding holes 20 in the feeding drum 5. At the end of the shaft 4 there is a sprocket wheel 21, which is engaged by a latch 22 pivoted into the key 16, said latch 22 being pressed against the sprocket wheel 21 by means of a spring 23. When the feeding drum 5 is turned clockwise, by means of the key 16, the feeding shoulder 11 moves along the guiding channel 8 in the direction of rotation until it strikes the guiding shoulder 13. The feeding spring 10 is now set. Because the shaft 4 is fixed to the case 1 the sprocket 21 with latch 22 prevent the spring 10 from bringing the feeding drum 5 back as long as the key 16 is retained in place. The cartridges 12 are arranged

side by side in the guiding channel 8. When the key 16 is removed from the case 1 the feeding spring 10 presses, by means of the feeding drum 5 and the feeding shoulder 13, the row of cartridges against the feeding chamber 14. The cartridge case is ready to be fired as soon as the case head 9 is now in place.

The construction principle of the cartridge case according to the modification illustrated by Figs. 4 and 5 is analogous with that described above. The principal difference is that there are two guiding channels radially arranged but so that they join from a single continuous irregular spiral channel 8. This channel 8 is made up by the partition-walls 25 and 26 in the case 1 and the case cover 9. The feeding drum 5 on the case shaft 4 is rotated by the feeding spring 10 around the shaft 4; the spring 10 tending to turn the drum 5 counter-clockwise. To the periphery of the feeding drum 5 there is fixed a small stirrup 27 in which a feeding lever 29 is pivoted on the pin 28. At the end of the lever 29, extending through the clearances 30 and 31 between the partition-walls 25 and 26 up to the outer feeding channel, there is a feeding cylinder 32 shaped in the form of the cartridge, the length of which is in excess of the thickness of the feeding lever 29 which is only slightly narrower than the clearances 31 and 32.

The cartridge case is filled in the way described above i. e. by removing the case cover 9 and setting by means of the case key 16, the pins 19 of which fit into corresponding holes 20 in the bottom of the feeding drum 5, the feeding spring 10 and locking the feeding drum 5 to the shaft 4 of the case 1. The cartridges 12 are arranged side by side in the feeding channel 8, when the cover 9 is now pressed into place and the key 16 removed. the feeding spring 10 forces, by means of the feeding drum 5, the feeding lever 29 and the feeding cylinder 32, the cartridges 12 into the feeding chamber 14 at the periphery of the cartridge case 1, from which chamber 14 the loading mechanism of the arm, operating in the aperture 15, presses the cartridges into the cartridge chamber of the weapon. It is to be noted that the pivoted lever 29 allows the feeding cylinder 32 to follow freely the guiding channel 8 despite the spiral form of the channel 8.

Fig. 6 illustrates the cartridge number indicator fitted to either one of the cartridge cases described above. In the bottom of the cartridge case 1 there is a hole 33 facing the feeding drum 5, the said hole being matched by figures in the feeding drum bottom in such a way that the figure (3) appearing in the hole 33 shows the number of cartridges still left in the drum.

It is of course possible to make modifications in details within the scope of the invention.

tion while still keeping to its principles. It is for instance possible to increase the turns of the spiral cartridge channel 8 in order to house a greater number of cartridges 12 by increasing the diameter of the case. The 70 guiding channels may also be arranged helically, in which case there must be a joint in the feeding lever 29 which allows the lever to swing also in the direction of the axis of the case. 75

I claim:

1. A cartridge magazine comprising a cylindrical case, a feeding drum mounted in said case of smaller diameter than said case thereby forming a cartridge channel, and 80 a rigid arm pivoted upon the outer periphery of said drum for feeding the cartridges in said channel.

2. A cartridge magazine comprising a cylindrical case, a feeding drum mounted in 85 said case of smaller size than said case, a spiral cartridge channel formed between the outer periphery of said drum and the inner periphery of said case, and a rigid arm pivoted upon the outer periphery of said drum 90 for feeding the cartridges in said channel.

3. A cartridge magazine comprising a cylindrical case, a feeding drum mounted in said case of smaller diameter than said case, partition walls upon said case located between the outer periphery of said drum and the inner periphery of said case, a slot provided in said partitions, and a rigid arm pivoted upon the outer periphery of said 95 drum adapted to extend through the said 100 slot in order to feed the cartridges in said channel.

4. A cartridge magazine comprising a cylindrical case, a shaft upon which said case is mounted, a feeding drum rotatably 105 mounted upon said shaft within said case, a ratchet wheel upon said shaft, a key member having lugs adapted to cooperate with said drum, a pawl carried by said key member for cooperating with said ratchet wheel, 110 a spring secured to said shaft and to said drum for rotating the same in order to feed cartridges, said key being adapted to maintain said drum in locked position against the action of said spring for loading said magazine with cartridges. 115

In testimony whereof I affix my signature.

AIMO JOHANNES LAHTI.
